CONTROL DEVICE AND SYSTEM

Harold Arthur Wheeler, Grand Rapids, Mich., assignor to Bendix Aviation Corporation, Teterboro, N. J., a corporation of Delaware

Application August 31, 1945, Serial No. 613,833

19 Claims. (Cl. 123—25)

1

The present invention relates to improved control devices and systems of the class disclosed by application Serial No. 508,724 filed November 2, 1943 and now abandoned and application Serial No. 551,036 filed August 24, 1944 by Howard A. Alexanderson and application Serial No. 598,767 filed June 11, 1945 by Harold A. Wheeler. More specifically, the present invention relates to a novel and improved control mechanism for a supercharged aircraft engine which provides means for effecting automatic control of two or more intake manifold pressure selection programs for such an engine in response to an operating condition thereof.

An object of the invention is to provide novel means responsive to the intake manifold pressure for adjusting a throttle valve so as to approximate predetermined pressure values together with a novel pair of adjustable members for selecting such pressure values and means for selectively actuating one or the other of said members into operating relation in response to an operating condition.

Another object of the invention is to provide a novel adjustment means for directly actuating an automatic carburetor throttle control in a first sense, and a second novel intake manifold pressure responsive means for directly actuating the throttle control in an opposite sense so as to maintain a predetermined selected pressure value, which value is variable in accordance with a first selected program, and adjustable means for varying such value in accordance with a second or more selected programs.

Another object of the invention is to provide a novel selector linkage arrangement, whereby the datum of the boost control may be selected in accordance with two or more predetermined programs.

Another object of the invention is to provide a novel control mechanism for selecting in accordance with a first selected program the intake manifold pressure of the aircraft engine, including novel adjustable means for varying the relationship of the intake manifold pressure of the aircraft engine in accordance with a second selected program brought into operation by a predetermined operating condition.

During the operation of the so-called "water" or "anti-knock" fluid injection systems for suppressing predetonation in internal combustion engines, an increase in the air inlet pressure of the induction system for the engine is permissible and desirable in order that greater engine power may be obtained than when such injection system is

2

not in operation. Therefore, an object of the present invention is to provide a novel regulator responsive to operation of such an injection system for effecting a predetermined increase in the air pressure in the induction system.

Another object of the invention is to provide a novel regulator for effecting smooth control throughout the range of operation of the "anti-knock" fluid injection system.

Another object of the invention is to provide a novel regulator for effecting automatic control in accordance with a first predetermined program during low speed supercharger operation, and automatic control in accordance with a second predetermined program during high speed supercharger operation.

Another object of the invention is to provide a novel regulator for effecting automatic control in accordance with a first predetermined program during operation of the supercharger at low speed; a second predetermined program during operation of the supercharger at high speed; and a third predetermined program during operation of the anti-knock fluid injection system.

Further, during the operation of the aircraft engine at high altitude it is desirable to operate the supercharger at greater speeds and the intake manifold pressure under a different selected pressure program than at lower altitudes. Accordingly, it is an object of the present invention to provide manually adjustable means or automatic altitude responsive means for effecting such operation.

These and other objects of the invention are pointed out in the following description in terms of the embodiment thereof which is shown in the accompanying drawings. It is to be understood, however, that the drawings are for the purpose of illustration only, and are not designed as a definition of the limits of the invention, reference being had to the appended claims for this purpose.

In the drawings:

Figure 1 is a sectional view showing the control mechanism;

Figure 2 is a sectional view taken along the lines 2—2 of Figure 1;

Figure 3 is an enlarged sectional view taken along the lines 3—3 of Figure 1;

Figure 4 is an enlarged perspective view illustrating schematically the cam follower linkage arrangement;

Figure 5 is an enlarged plan view of the leaf spring arrangement for the cam follower arms;

Figure 6 is a diagrammatic view of the operating mechanism;

Figure 7 is a schematic view showing the control mechanism in operative relation with the aircraft engine controlled thereby;

Figure 8 is a diagrammatic view of an altitude responsive device for controlling the speed of the supercharger and effecting the operation of the regulator;

Figure 9 is a graphical illustration of the operating characteristics of a typical control mechanism embodying the present invention.

The control mechanism as shown in Figures 6 and 7 is preferably operated by a main control lever 1 pivotally mounted at 2 within the cabin of an aircraft. There is pivotally connected to the control lever one end of a main control rod 3.

As shown in Figure 6, there is pivotally connected at the opposite end of the main control rod 3 at 4, an arm 5 mounted on a main control shaft 6 and positioned exteriorly of a casing 7 as shown in Figure 7. The casing 7 houses the novel control mechanism and may be conveniently mounted on a bracket 7A as shown in Figures 1 and 7.

As shown in Figures 6 and 7, there is formed integral with the arm 5, a second arm 8 likewise mounted on the main control shaft 6 and positioned exteriorly of the casing 7. Movement of the arm 8 may be limited as indicated in Figure 6 by a stop 9 which is arranged for engagement by an adjustable limit screw 9A provided on the arm 8 and a second engaging arm 10 formed integral with the arm 8.

The main control shaft 6 extends into the casing 7 and is rotatably mounted on suitable antifrictional bearings, not shown.

Positioned within the casing 7 and fixedly mounted at the inner end of the main control shaft 6 is a crank pin 11, as best shown in Figures 1 and 6. The crank pin 11 has pivotally mounted at the free end thereof a walking beam 12. The walking beam 12 is pivotally connected at one end to a link 13 which is in turn pivotally connected at the other end to an arm 14 of a bell crank lever 15, as shown in Figures 1 and 6. The bell crank lever is mounted on a shaft 16.

The shaft 16 is mounted on antifrictional bearings, not shown, and projects through the casing 7, as shown in Figure 6. Mounted at the outer end of the shaft 16 is an arm 17 having pivotally connected at the free end a throttle control rod 18 for adjustably positioning a throttle valve 19 positioned within the air intake conduit of a conventional aircraft internal combustion engine, as indicated diagrammatically in Figure 7.

The throttle valve 19 is arranged so as to regulate the pressure at the intake manifold 20 of an engine 21 by regulating the air inlet through conduit 22 to a supercharger 23. The supercharger 23 is driven by the aircraft engine 21 through a drive shaft 25 and change speed gear or hydraulic coupling 26. The supercharger 23 is arranged to supply air to the intake manifold 20. A carburetor 27 is provided in conduit 22 of conventional type and a conduit 28 leads from the carburetor 27 to a suitable air supply or air intake scoop 29.

Pivotally connected to the arm 8, previously described, is one end of a linkage rod 30. The opposite end of the rod 30 is pivotally connected to one end of a lever arm 31 mounted on a pressure selector shaft 32, as shown in Figure 6. The shaft 32 projects into the casing 7 and is preferably mounted therein on bearings 32A and 32B, as shown in Figure 3.

The shaft 32 has fixedly mounted thereon, cams 33 and 34 which may be adjustably positioned by the adjustment of the shaft 32. The cams 33 and 34 have provided variable cam surfaces 36 and 37, respectively, which are arranged to bear upon cam follower members 38 and 40 as will be explained hereinafter, so as to operably connect the shaft 32 to an adjustable frame or lever member 42. As shown in Figure 2, the lever 42 is pivotally mounted within the casing 7 on a shaft 43.

There is connected to the lever 42 at the lower end, as viewed in Figure 4, a spring 44. The spring 44 is coiled about the shaft 43 and one end 45 bears upon a fixed member 46, while the opposite end 47 biases the lever 42 in a counter-clockwise direction about the shaft 43. Projecting from the lever 42 at a point intermediate the opposite ends thereof is a pin 48 to which there is pivotally connected an end 49 of a novel range adjustment floating lever 50, as shown in Figure 6.

The floating lever 50 is pivotally connected at a point 51, intermediate its opposite ends to one end of a linkage arm 52. The linkage arm 52 is operatively connected at the opposite end to a pressure responsive mechanism indicated generally by the numeral 53 which will be described hereinafter.

Servomotor Mechanism

30 A third link 54 is pivotally connected at one end to the floating lever 50 at an end 55 opposite from the end 49. The opposite end of the link 54 is affixed to a slidably adjustable member 56 for controlling a servo-valve of conventional type. 35 As shown in Figure 1, the member 56 is slidably mounted within a valve sleeve 56A, positioned within the wall of the casing 7. Carried by the servo-valve control 56 is a tension spring 57 which exerts a force biasing the link 54 toward the floating lever 50. The valve sleeve 56A has provided ports 58, 59, 60, 61 and 62, as shown in Figures 1 and 6. The ports 59 and 61 are connected by suitable conduits 63 and 64, respectively, to a servo-motor indicated generally by the numeral 65, while a conduit 66 is connected to the port 60 and serves as an inlet to the servo-valve of a suitable fluid medium under pressure such as oil under engine pressure for operation of the servo-motor 65. A drain conduit 67 is further connected to the ports 58 and 62 and serves as an outlet for the fluid pressure medium supplied to the servo-valve in the conventional manner.

As shown in Figures 1 and 6, a servo-piston 68 is slidably mounted within a cylinder wall 69 of the servo-motor 65. The piston 68 is connected to a piston rod 70 in any conventional manner. A tension spring 71 biases the piston 68 in a direction tending to slide the rod 70 outwardly from the cylinder 69 for a purpose which will be explained hereinafter. Movement of the piston 68 in response to the biasing force of the spring 71 is limited by a collar 72 against which the piston 68 abuts in the extreme biased position.

As shown in Figure 1, suitable telescoping tubular members 73 and 74 are provided for protecting the spring 71 and limiting the extent of movement of the piston 68 in the opposite direction.

The conduits 63 and 64, previously described, lead to opposite sides of the piston 68 so that adjustment of the servo-valve control 56 to the left of the neutral position shown in Figure 6, will cause the conduit 63 to serve as an inlet of pressure to the servo-motor 65 and thereby exert a biasing force upon the piston 68 to the right. 75 Likewise, adjustment of the servo-valve control

60 to the right of the neutral position shown in Figure 6, will cause the conduit 64 to serve as an inlet of pressure to the servo-motor 68 and exert biasing force upon the piston 68 to the left. Thus it will be seen that in the conventional manner the direction of movement of the piston rod 68 may be controlled by the adjustment of the servo-control valve 56.

While there has been shown in the present embodiment of the invention a hydraulic control and power means, it will be readily seen that other forms of controls and power means such as well known, mechanical and electronic controls and power means, may be readily substituted therefor.

It will be further noted that the outer end of the piston rod 70 under control of the power means aforesaid, is pivotally connected by a link 75 to the opposite end of the walking beam 12 from that at which the link 13 is connected, as previously described. It will thus be seen that the adjustment of the walking beam 12, and accordingly the throttle control shaft 16 is dependent upon the effect thereon of the adjustment of the main control shaft 6 and the servo-motor 65.

The adjustment of the servo-motor 65 is dependent upon the adjustment of the pressure selector cam 33 or 34, previously described; the position of the pressure responsive mechanism 53, as will be further described, in relation to the adjustment of the pressure selector cam and upon the adjustment of the main control shaft 6 irrespective of the position of the pressure selector cam or the pressure responsive mechanism 53, as will be explained.

Pressure responsive mechanism

The pressure responsive mechanism 53, previously noted, comprises preferably a pair of bellows 76 and 77 mounted within the casing 7, as best shown in Figure 1. The bellows 77 is preferably partially evacuated and balanced by a coil spring 78 mounted within the bellows 77 so as to act against the biasing force of the bellows 76. A wall 79 formed within the casing 7 has mounted thereon the bellows 76 which is connected through a passage 80 passing through the wall 79, and a conduit 81 connecting the passage 80 to the intake manifold 20 of the internal combustion aircraft engine 21, as shown in Figures 1, 6, and 7, in such a manner that the biasing force of the bellows 76 will vary in response to the intake manifold pressure. A plate 82 is mounted between the bellows 76 and 77 and is movable upon variance in the pressure exerted within the bellows 76, as is well known in the art. The plate 82 has provided a projecting arm 83 to which there is pivotally connected an end of the linkage arm 52 previously described. The opposite end of the bellows 77 is mounted on a plate 84 secured in the side wall of the casing 7 as shown in Figure 1.

From the foregoing it will be seen that the adjustment of the servo-valve control 56 will be dependent upon the intake manifold pressure acting upon the pressure responsive mechanism 53 and the corresponding adjustment thereof in relation to the adjustment of operating cams 33 or 34. It should be pointed out here that the tension exerted by the spring 44 and acting upon the arm 36, has a considerably greater biasing force upon the servo-control valve member 56 than the force exerted thereon by the relatively

5 light tension spring 57 mounted on the member 56.

Thus it will be seen that in normal operation a decrease in the intake manifold pressure due to a rise in altitude for example, decrease in atmospheric pressure or other cause, would affect the bellows 76 and 77 so as to cause the relative contraction of the bellows 76 and the relative expansion of the bellows 77. Such action would cause the movement of the plate 82 and the longitudinal movement of the linkage arm 52 toward the left, as viewed in Figures 1 and 6.

Since, as previously explained, the spring 44 exerts a greater biasing force than the spring 57, it will be readily seen that such longitudinal movement of the arm 52 would cause the floating lever 50 to pivot in a counterclockwise direction on its pivotal connection to the arm 42 resulting in a corresponding longitudinal movement of the link 54 and servo control valve member 56 to the left.

Thus with the control valve member 56 first in the neutral position, such adjustment of the servo control valve member 56 would cause the opening of the port 59 to the inlet of the pressure medium provided through the port 60 resulting in the shifting of the piston 68 to the right as viewed in Figures 1 and 6 and the mechanical adjustment of the throttle 19 to a relative increased open position through the action of the piston rod 70 on the link 75, walking beam 12, link 13, bell crank lever 15, throttle control shaft 16, arm 17, and rod 18, and thereby increasing the pressure exerted at the intake manifold 20.

Conversely, an increase in the intake manifold pressure would cause the relative expansion of the bellows 76 and contraction of the bellows 77, resulting in the longitudinal movement of the linkage arm 52 to the right.

Obviously, since the movement of the lever arm or frame 42 would be prevented by the spring 44, the latter adjustment of the linkage arm 52 would cause the clockwise movement of the floating lever 50 about its pivotal connection 48 to the arm 42, causing a corresponding longitudinal movement of the servo-control valve member 56 to the right. Thus with the control valve member first in the neutral position, such adjustment of the servo-control valve member 56 would cause the opening of the port 61 to the inlet of the pressure medium provided through the port 60 causing a shifting of the piston 68 and the mechanical adjustment of the throttle 19 to a relative decreased open position and thereby decreasing pressure exerted at the intake manifold 20.

Thus it will be seen that there is provided automatic means for compensating for either an increase or decrease in the pressure at the intake manifold 20, so that a predetermined standard pressure condition may be approximated. Obviously, upon standard pressure conditions being approximated, the pressure responsive mechanism 53 will cause the adjustment of the servo-control valve member 56 to a neutral position.

It will be further seen that there has been provided adjustment means whereby the value of the predetermined standard pressure condition may be varied. Thus upon movement of the control lever 1, as shown in Figures 6 and 7, in a counterclockwise direction, a clockwise movement of the main control shaft 6 will result, causing a corresponding clockwise movement of the walking beam 12 about its pivotal connection to the link 75 and causing in turn the clockwise movement

of the throttle control shaft 16 so as to move the throttle 19 to a relative open position.

Furthermore, it will be seen that such adjustment of the control arm 1 will cause also the clockwise movement of the arm 8 and a corresponding counter-clockwise rotation of the cams 33 and 34, as viewed in Figure 6, for changing the datum or setting of the pressure responsive mechanism 53.

Pressure selection mechanism

The cams 33 and 34 are operably connected to the adjustable frame or lever 42 through the cam follower members 39 and 40 which project respectively from arm members 85 and 86, shown in Figures 1, 2 and 4. The arm members 85 and 86 are freely mounted respectively in spaced relation on the shaft 43. The frame or lever member 42 includes, as best shown in Figure 10, arm portions 88 and 89 provided at opposite ends of the shaft 43, and having the upper and lower ends thereof connected respectively by plates 90 and 91.

The upper ends of the arm members 85 and 86 have end portions 92 and 93 projecting laterally therefrom and arranged to contact the ends of adjustable screws 95 and 96 which project through the top plate 90. The cam follower arms 85 and 86 are spring loaded in a clockwise direction under the biasing force of spring fingers 98 and 99, respectively. The spring fingers 98 and 99, as shown in Figures 2, 4, 5 and 6 project from a spring plate 101 fastened at opposite ends by bracket arms 102 and 103 which project from a bracket plate 104, as shown in Figure 3. The plate 104 is secured to the inner surface of the casing 7, by bolts 105 and 106, and dowel pins 107 and 108. There also projects from the plate 104 the fixed arm members 46 and 46A in which is screw threadedly engaged the opposite ends of the shaft 43, as best shown in Figure 2.

As thus shown, the spring fingers 98 and 99 tend to bias the cam follower members 85 and 86 in a clockwise direction into contacting relation with the adjustable screws 95 and 96 respectively, projecting from the plate 90 of the frame or lever 42. The lever 42 is biased by the spring 44 in an opposite counter-clockwise direction, as viewed in Figure 4, but the force exerted by any one of the spring fingers 98 and 99 through the cam follower arms 85 and 86 exceeds the force exerted by the spring 44 on the plate 90 so that the frame 42 is biased in a clockwise direction under the force of the same against the force exerted by spring 44.

It will be noted moreover, that the movement of the cam follower arms 85 and 86 are limited, as shown in Figure 6, by the cams 33 and 34 which contact respectively the cam follower members 39 and 40 so that the counter-biasing force exerted through any one cam follower arm and the position of the lever member 42 is dependent upon the cam surface controlling the controlling cam follower arm.

It will be noted, moreover, that as the lever member 42 moves in a clockwise direction about the shaft 43, the pressure setting of the bellows 53 is increased. Thus the highest pressure setting is obtained at the lowest cam rise, while the lowest pressure setting results at the highest cam rise.

It will be readily seen from Figures 1 and 6 that as the control lever 1 is adjusted in a counter-clockwise direction the shaft 32 is adjusted in a counter-clockwise direction and thereby decreasing the cam rise of the respective cams 33

and 34. The cam surfaces 36 and 37 are arranged so as to provide a different cam rise program so as to effect a different program of pressure settings from the other cams, when brought into operating relation with the lever 42 through the cam follower arms 85 and 86.

There is further provided novel means for selectively placing one or the other of the cams in an operating relation. The cam surface 35 of the cam 33 is arranged so as to provide the lowest cam rise or highest pressure setting program of the two cams, while the cam surface 37 of the cam 34 is arranged to provide a higher cam rise and accordingly a lower pressure setting program.

There is further freely rotatable on the shaft 43 an arm 109 carrying a plate 110 as shown in Figures 2, 4 and 6. Screw threadedly engaged in the plate 110 and projecting through the same are adjustable screws 111 and 112 which are arranged so as to operably contact the cam follower arms 85 and 86. A spring 113 coiled about the shaft 43 has one end portion 114 bearing upon the cam follower member 86 and biasing the same in a clockwise direction, while another end 115 of the spring 113 bears upon the arm 109 and biases the plate 110 in a clockwise direction and the adjustment screws 111 and 112 out of contacting relation with the cam follower members 85 and 86.

As shown in Figures 4 and 6, the arm member 109 has a raised portion 116 arranged so as to be operably engaged by one end of a piston rod 117. The piston rod 117 is connected at the opposite end to a cup shaped piston 118 slidably mounted in a piston chamber 119 formed in the end wall 35 of the casing 7.

A fluid pressure inlet passage 120 is formed in the end wall of the casing 7 and opens at one end into the piston chamber 119. The opposite end of the passage 120 as shown in Figure 2, is controlled by a valve mechanism indicated generally by the numeral 121 so as to open and close the passage 120 to a suitable fluid medium under pressure such as oil under engine pressure. The latter fluid pressure medium is supplied through a second passage 122 formed in the casing 7 and into which opens an oil pressure conduit 123 leading from the source of pressure. The latter fluid medium under pressure provides means for operating the piston 118. The cup shaped piston 118 has a restricted orifice 124 formed in the bottom thereof for draining the fluid medium from the cup shaped piston 118 into the interior of the casing 7, where the same is drained from the casing 7 through suitable passages not shown.

Thus upon the valve 121 being opened the fluid medium or oil under pressure passes through the passage 122, valve 121, passage 120 and into the piston chamber 119 biasing the piston 118 towards the left as viewed in Figure 6. The latter action of the piston 118 forces the free end of piston rod 117 into contact with the raised portion 116 of the arm member 109 forcing the arm 109 in a counter-clockwise direction and the limit screws 111 and 112 to a predetermined position where the same serve to limit the movement of cam follower members 36 and 37 in a clockwise direction.

During the latter action, as the biasing force exerted by the spring fingers 101 on the lever 42 is removed, the frame or lever member 42 is biased under force of the spring 44 in a counter-clockwise direction following the movement of arm 109. When a point is reached where the end of the screw 95 or 96 contacts its respective cam follower arm 85 or 86 as the case may be, such move-

ment of lever 42 stops. Further movement of the frame or lever 42 is then prevented by the force exerted by the spring fingers 101, which biases the cam follower arms in a clockwise direction. The position of the cam follower arm 85 or 86 is determined by the cam surface of the controlling cam, subject to the limit of action of the limit screws 111 and 112 as explained.

The piston 118 thus under force of the fluid pressure biases the arm 109 to an operative position relative to the cam follower arms 85 and 86 so as to limit the movement thereof in a clockwise direction. However, upon the valve 121 being closed the spring 113 biases the piston 118 through arm 109 and rod 117 to a return position; the fluid medium within piston 118 being forced out through the restricted passage 124 under the biasing force of spring 113 and the cam follower arms under spring fingers 101 are biased to a position at which the cam follower members once again contact the cam surfaces of their respective control cams. The passage 124, however, is sufficiently restricted as not to effect the position of the piston 118 upon the valve 121 being opened and the pressure medium or oil being exerted upon the piston 118 through the passage 120.

The latter limiting action of the adjustment screws 111 and 112 provides releasable means for limiting the maximum pressure setting afforded by the arms 85 and 86. The limiting means is effective only within a predetermined maximum adjustment range of the control lever 1 and may be readily cut out of operation by the closing of the valve 121 for a purpose which will be explained hereinafter.

The cam follower arm 85 has a raised portion 129 arranged so as to be operably engaged by one end of a piston rod 130. The piston rod 130 is connected at the opposite end to a cup shaped piston 131 slidably mounted in a piston chamber 132 formed in the end wall of the casing 7.

There is formed in the casing 7 a passage 133 opening into the chamber 132 for conducting a fluid medium under pressure such as oil under engine pressure into the piston chamber 132. The latter pressure medium is conducted to the passage 133 through a suitable conduit 134, as shown in Figure 7, having a slide valve 135 for controlling the application of pressure through said conduit 134 from a main pressure line 136 as will be explained.

Upon the valve 135 opening the conduit 134 to the pressure line 136, the fluid medium entering the piston chamber 132 through passage 133 will bias the piston 131 towards the left as viewed in Figures 1 and 6 causing the free end of the piston rod 130 to contact the raised portion 129 of the cam follower arm 85 forcing the arm 85 and cam follower member 39 out of contacting relation with the cam surface 36 of the cam 33 and in a counter-clockwise direction. During the latter action, as the biasing force exerted by the spring finger 98 on the lever 42 is removed, the frame or lever member 42 is biased under force of the spring 44 in a counter-clockwise direction following the movement of cam follower arm 85. When a point is reached where the end of the screw 96 contacts the projection 93 of the cam follower arm 86 such movement of lever 42 stops. Further movement of the frame or lever 42 is then prevented by the force exerted by the spring finger 99, which biases the cam follower arm 86 in a clockwise direction. The position of the cam follower arm 86 is determined by the cam surface 37 of the cam 34 which contacts

the cam follower member 40 projecting from the arm 86.

The cup shaped piston 131 has a restricted passage 137 formed in the bottom thereof for draining the fluid medium from the piston 131 into the interior of the casing 7, where the same is drained from the casing 7 through suitable passages not shown. The passage 137, is however sufficiently restricted as not to effect the position of the piston 131 upon the valve 135 opening the conduit 134 to the pressure medium.

The piston 131, thus under force of the fluid pressure, biases the arm 85 to an inoperative position relative to the frame 42. However, upon the valve 135 closing the conduit 134 to the pressure medium in the line 136, the spring finger 98 biases the piston 131 through arm 85 and rod 130 to a return position, the fluid medium within piston 131 being forced out through the restricted passage 137 under the biasing force of spring 98 and the cam follower arm 85 being biased to a position at which the cam follower member 39 once again contacts the cam surface 36 of cam 33.

Upon the cam follower arm 85 being placed in an inoperative relation to the lever 42, the cam follower arm 86 is placed in operative relation to the lever 42 and the cam surface 37 of cam 34 controls through cam follower member 40 the pressure setting of the bellows 53, which follows a lower pressure setting program than when cam 35 controls through arm 85.

Water injection system

As best shown schematically in Figure 7, there is connected to the carburetor 27 a conduit 140 leading from a suitable source of fluid fuel for the aircraft engine. There is also provided a conduit 141 for injecting the fuel into the induction system through a nozzle 142. There is further provided a conduit 143 for injecting into the induction system through nozzle 142 a supplemental or so-called "anti-knock" fluid medium such as water, water-alcohol or other suitable fluid well known in the art for suppressing pre-detonation of the engine 21.

The conduit 143 is connected to a suitable metering device shown in dotted outline and indicated generally by the numeral 144. The latter metering device may be of a suitable type well known in the art for determining the rate of flow of the "supplemental" fluid, and, since the present invention resides in the regulator means rather than in the metering device, the same has been shown diagrammatically by the outline indicated by numeral 144.

A conduit 145 leads to the metering device 144 from a suitable source of "supplemental" fluid indicated by numeral 146. In the conduit 145, there is provided a pump indicated by numeral 147 driven by a suitable power means not shown. The pump 147 supplies the fluid medium under pressure to the metering device 144. A valve 148 is provided in the conduit 145 between the pump and metering device 144 for "off" and "on" control of the "supplemental" fluid injection system. The control valve 148 may be of any suitable type, but is shown herein as of an electromagnet controlled type having an electrical control circuit 149 and switch 150 which is preferably mounted within the aircraft cabin for convenient operation by the pilot. Thus the supplemental fluid injection system may be placed in operation by the pilot closing the switch 150 so as to effect the opening of the valve 148. Conversely, the valve 148 may be closed by opening

the switch 160. A by-pass conduit 151 and relief valve 152 is provided for recirculating the fluid medium from the pump outlet to the pump inlet at such times as the valve 148 is closed and the injection system is not in operation.

A conduit 153 is connected to the conduit 145 between the valve 148 and the metering device 144. The conduit 153 leads to a control mechanism 154 arranged so that during operation of the injection system, the control valve 124 is closed by the pressure of the supplemental fluid medium acting under force of the pump 25, as will be explained hereinafter. It will be readily seen that when the injection system is in operation the fluid medium will exert through the conduit 153 a greater pressure under force of the pump 147 than when the injection system is not in operation.

Control mechanism responsive to operation of water injection system

The control valve mechanism 154 includes, as shown in Figure 2, a plug 155 screw threadedly engaged in the casing 7 and projecting into the passage 122. The plug 155 has formed therein a passage 156 extending vertically therein and opening at the opposite ends of the plug 155. The plug 155 has lateral ports 157 formed therein and leading from the passage 122 into the vertical passage 156. A stem 158 is slidably mounted in the passage 156 and has a stem valve 159 at the lower end arranged upon the extreme inward adjustment of the stem 158 to close the lower end of the passage 156 to the passage of fluid medium from passage 122 to passage 120.

The upper end of the stem 158 has affixed thereto a head member 159. A spring 160 has one end bearing upon the plug 155 while the opposite end bears upon the head member 159 biasing the stem 158 in an upward direction as viewed in Figure 2. The head member 159 and spring 160 are positioned in a chamber 161 formed in the casing 7. Across the chamber 161 extends a diaphragm 162 clamped at the outer edge between the casing 7 and a cap member 163 fastened to the casing 7 by suitable bolts 164. The cap member 163 has formed therein a recess 165 and opening into the recess 165 is the conduit 153.

The diaphragm has a button 166 which bears upon the head member 159 of the stem 158. A suitable orifice or passage not shown, opens the chamber 161 to atmospheric pressure or other suitable reference pressure.

Thus upon operation of the water injection system there is effected an increase in the water pressure exerted in the chamber 165. The diaphragm under such increased pressure actuates the stem 158 so as to cause the valve stem 159 to close the lower open end of the passage 156, and thereby the passage 120 to the pressure medium.

The latter action as previously explained will release the pressure tending to hold the arm 109 in a position for limiting the maximum pressure setting, whereupon cams 34 or 35, through cam follower members 40 or 41 may effect a higher pressure setting of the bellows 53 during operation of the water injection system.

Upon the valve 148 being closed by the pilot so as to terminate the operation of the water injection system, the pressure applied through conduit 153 will decrease whereupon the diaphragm 162 and valve stem 158 under force of the spring 160 will be forced upward in a direc-

tion opening the passage 156 to the fluid pressure medium in passage 122. The latter action will cause piston 118 to position the arm 109 so as to limit the maximum pressure setting, as previously explained.

Control mechanism responsive to operating condition

As shown in Figure 7, there leads from the pressure conduit 134 which controls the operation of piston 131, a second conduit 170. The conduit 170 opens into a piston chamber 171 of a servomotor 172. Slidably mounted in the piston chamber 171 is a piston 173 having a spring 174 biasing the same in one direction, while the fluid medium entering through the conduit 170 biases the piston 173 in the opposite direction. A conduit 175 leads from the servo valve 135 and opens at the other side of the piston 173.

A piston rod 176 extends from the piston 173 and operates an arm 177 of a change speed gear or variable speed hydraulic coupling 26 through which the engine 21 drives the supercharger 23.

The servo valve 135 has pressure outlet conduits 178 and 179 and may be manually operated by the pilot through a push rod 180 from the cabin of the plane.

When the valve 135 is shifted to the left as viewed in Figure 7, a fluid pressure medium such as oil under engine pressure may be applied through the conduit 175 to the lower side of the piston 173, whereupon the fluid medium at the upper side will exhaust through conduit 170 and outlet conduit 179.

The latter action causes the piston 173 to adjust the arm 177 in a clockwise direction to the position shown, at which position the supercharger 23 may be driven by shaft 25 through the variable speed coupling 26 at a relatively low speed ratio.

In the latter case, it will be seen that the conduits 134 and 170 are closed to the fluid pressure medium in the conduit 136 and the cam 33 will control through cam follower member 39 and arm 85 the pressure setting of the bellows 53 during the low speed operation of the supercharger 23. The latter control cam 33 will effect a relatively high pressure setting during the low blower operation.

Now upon the pilot shifting the valve 125 to the right as viewed in Figure 7, the fluid pressure medium supplied through conduit 136 will be applied through conduit 170 so as to shift the piston 173 downward and moving the arm 177 in a counter-clockwise direction.

The fluid medium at the lower side of the piston 173 will exhaust through conduit 175 and outlet conduit 178. The latter adjustment of the arm 177 will cause the variable speed coupling 26 to be shifted so that the supercharger may be driven by shaft 25 through the variable speed coupling 26 at a relatively high speed ratio.

Moreover, the fluid pressure medium when applied through conduit 170 will also cause a fluid pressure to be applied through conduit 134 and passage 133 forcing the piston 131 in a direction for actuating the cam follower arm 86 out of operative relation with the cam 33.

Thus upon the supercharger 23 being driven at a high speed ratio, or high blower operation, the cam 34 will control through arm 86 the pressure setting of the bellows 53. The latter control cam 34 will effect a relatively low pressure setting during the high blower operation.

The supercharger 23 is normally brought into high blower operation at relatively high altitudes,

while low blower operation is effected at relatively low altitudes. It is desirable under such conditions to provide a relatively low pressure setting at high altitudes, while a higher pressure setting is desirable at relatively low altitudes. Through the novel cam selection means provided herein, a higher pressure setting program is provided during low blower operation than during high blower operation.

In Figure 8, there is shown novel means for effecting such operation automatically. In the latter arrangement, there is provided a casing 181 open through a conduit 182 to atmospheric pressure. Mounted within the casing 181 is a bellows 183 of conventional type and operably connected so as to position the control valve 135. Thus at low altitudes the bellows 183 tends to collapse, moving the valve 135 so as to open conduit 175 to the fluid pressure medium in passage 136. This action causes the servomotor 172 to adjust the variable speed coupling 26 so as to effect low speed operation of the supercharger 23. However, at a predetermined low atmospheric pressure or high altitude the bellows 183 expands sufficiently to adjust valve 135 so as to open conduit 170 to the pressure medium in conduit 136 and close conduit 175 to such fluid pressure.

Upon the latter operation the variable speed coupling is adjusted by the servomotor 172 so as to effect high speed operation of the supercharger 23. In the latter event there will be applied a fluid pressure medium through conduit 124 to shift the low blower cam follower arm 85 out of operation, and the cam follower arm 86 into an operative relation with lever 42 during high blower operation.

Lock out limiting means

There is further provided means to lock out the automatic means, whereby upon adjustment of the main control lever 1 to a predetermined minimum standard pressure selecting position, the opening of the throttle 19 may be effected only by the manual adjustment of the control lever 1 without regard to the pressure existing at the intake manifold, or the condition of the pressure responsive mechanism. This is specifically accomplished by providing an adjustable abutment rod 190 best shown in Figures 1 and 6 and explained in detail in the copending application of Howard A. Alexanderson, Serial No. 508,724, filed November 2, 1943. The abutment rod 190 is screw threaded engaged in the wall 79 and projects through the wall 79 into the bellows 76. A suitable cleft 191 is provided in the abutment rod 190 and is positioned exteriorly of the bellows 76 so that the abutment rod 190 may be conveniently adjusted longitudinally for calibration purposes. The abutment rod 190 is arranged so as to engage the plate 82 upon the pressure in the intake manifold decreasing to a predetermined low value equal to the critical standard value at which the automatic control for opening the throttle is to be discontinued and manual control alone remains.

A second abutment rod 193 is also mounted within the bellows 77 as shown in Figure 1, for the purpose of limiting the excessive expansion of bellows 76 and contraction of bellows 77 which might otherwise cause mechanical damage thereto.

There is further provided a third safety means for preventing the automatic opening of the throttle 19 past a predetermined maximum critical point, and the said safety means so arranged that

such opening of the throttle past such point, may only be accomplished under the positive manual control of the lever 1.

This function is specifically accomplished by providing the bell crank lever 14, previously described, with a knocker arm 194 arranged for actuating the arm 195. The arm 195, as shown in Figures 1 and 7, is pivotally mounted at one end on an eccentric pin 196 carried by an adjustment screw 197. The adjustment screw 197 is screw threaded engaged in the wall of the casing 7. The position of the arm 195 in relation to the knocker arm 194 may be conveniently adjusted for calibration purposes by means of the screw 197 which extends through the wall of the casing 7 to the exterior, as shown and described in detail in the copending application of Howard A. Alexanderson, Serial No. 508,724, filed November 2, 1943.

Carried by the arm 195 is a pin 198 on which is mounted a roller 199 arranged for engagement by the knocker arm 194, as shown in Figures 1 and 7. There further projects from the arm 195, a member 200 which is arranged to engage a valve actuating stop pin 201 slidably mounted within a sleeve member. The stop pin 201 projects through the sleeve into the valve sleeve 56A where it is adapted to engage in its inward position, the free end of the servo control valve rod 56. The pin 201 is normally biased by a spring 202 into a disengaging relation from the rod 56. In the latter position the pin 201 under the biasing force of the spring 202 actuates the arm 195 in a counter-clockwise direction against a stop pin 203 mounted in the wall 7. Upon the throttle 19 being opened to a predetermined point the bell crank lever 15 will be positioned so as to cause the knocker arm 194 to engage the roller 199 mounted on the arm 195. Continued clockwise adjustment of the bell crank lever 15 will cause arm 195 to actuate the pin 201 inward so as to prevent control valve rod 56 from being adjusted through the lever 50 to a position to the left of the neutral position. In the latter locked position a decrease in pressure at the intake manifold 20 would cause merely a contraction of the bellows 76 and the actuation of the lever 50 so as to cause the movement of the lever 36 in a counter-clockwise direction against the biasing force of the spring 42. Further clockwise movement of the bell crank lever 15 will cause the pin 201 to actuate valve rod 56 to the right of the neutral position and the piston 68 to the extreme left hand position shown, whereupon further opening of the throttle valve 19 may be directly effected by manual operation of lever 1.

Operation

The present invention provides novel means for control of various operating characteristics of aircraft engines and provides means specifically for controlling automatically two or more manifold pressure selection programs.

While the present embodiment of the invention is shown as applied to a single stage supercharger with a variable speed drive it will be readily apparent that the same may be also applied to (1) a single stage supercharger driven by a two speed engine; (2) a two stage supercharger with a two speed drive on the auxiliary stage or a variable speed drive; (3) an auxiliary stage turbo-driven supercharger or; (4) the invention may be applied as means for controlling automatically two or more selection programs.

As shown in Figure 6, the cam shaft 32 oper-

ated from the main control lever 1 may control any number of cams desirable for the various engine functions or manifold pressure programs. In the present embodiment of the invention, two such cams 33 and 34 are shown. Each cam operates individual cam followers, indicated herein by the numerals 85 and 86 which are spring loaded to the cams by separate finger springs 98 and 99, respectively. A pressure adjusting lever 42 is biased under tension of a spring 44 into contacting relation with whichever of said cam followers is positioned so as to select the highest pressure setting.

The high blower cam follower 86 remains in contacting relation with its cam 34 during both operating programs. The low blower cam follower 85 has hydraulic piston 131 for releasing it from selecting or contacting the profile of cam 33.

In high blower operation, the cam follower 85 is released from contacting its cam 33 by operation of the piston 131, and the high blower cam follower 86 is positioned by cam 34 so as to control the pressure adjusting lever 42.

During low blower operation, the low blower release piston 131 automatically allows follower 85 to contact the cam 33 and to control the position of the pressure adjusting lever 42. The low blower cam 33 thus controls through cam follower 85 and lever 42 the pressure setting throughout its range of operation. While the high blower cam follower 86 is in contacting relation with cam 34, the cam selecting the highest pressure setting controls the position of the lever 42.

While the water injection system is not in operation, the piston 118 holds the lock out member 109 so as to prevent the selected pressure from exceeding a predetermined value, the screws 111 and 112 limiting the movement of cam follower members 85 and 86.

Upon operation of the water injection system, the piston 118 automatically allows followers 85 and 86 to contact their cams within maximum limited range. Cam 33 selects a higher pressure setting than the cam 34. Thus, while both cams may be positioning their respective cam followers, the follower 85 under control of cam 33 calls for a higher setting than the other and therefore dominates the control of the pressure adjusting lever 42, until such time as follower 85 is cut out of operation.

The low blower release piston 131 is operated by oil pressure to the piston when the supercharger is operated at high blower. In low blower operation a control valve 135 is so arranged as to place the piston 131 under oil drain pressure so as to release the follower 85. The control valve 135 may be manually controlled as in Figure 7 or may be controlled by an atmospheric pressure or altitude responsive device as in Figure 8.

The piston 118 is operated by oil pressure applied to the piston 118 so as to maintain the member 109 in a limiting relation when the water injection pressure is off as during non-operation of the water injection system. This is accomplished by a diaphragm controlled valve 121. One side of the diaphragm 162 is subjected to water pressure, the other side to atmospheric pressure or other suitable reference pressure. Upon the water injection system being placed in operation, the increased water pressure causes the valve 121 to be closed so that the oil pressure is released from the piston 118 permitting the member 109 to be biased by spring 113 out of lim-

iting relation with the cam follower members 85 and 86, so that the controlling cam may adjust the same to a higher pressure setting than would be otherwise permissible.

However, upon the operation of the water injection system being discontinued the water pressure applied to the diaphragm 162 is released and the valve 121 is opened so that oil pressure may once again be applied to the piston 118 so as to place the member 109 in a limiting relation once again.

While hydraulic means has been shown for effecting the foregoing operation, it will be readily seen that the same may be also effected through 15 electrically operated solenoids, air pressure or manual linkage and may be applied in selecting for electric, electronic or hydraulic control systems.

Graphical illustration of operation

In Figure 9, there is illustrated graphically the operating characteristics of a typical control mechanism embodying the aforesaid invention.

Line A of the above graph illustrates the pressure setting program of the low blower cam 33 which predominates until such time as the supercharger is placed in high blower operation, whereupon the cam follower 85 will be placed out of operation. The cam 34 will then control the 30 pressure setting through cam follower 86.

Line B of the aforesaid graph illustrates the pressure setting program of the high blower cam 34.

The letter C on the line B indicates the point 35 at which the screw 112 of the member 109 may limit the maximum pressure setting under high blower operation during the non-operation of the supplemental fluid injection system. The letter D in the line A indicates the point at which the screw 111 of the member 109 may limit the maximum pressure setting under low blower operation during non-operation of such system.

Upon operation of the supplemental fluid injection system the pressure setting may be increased as indicated by the dotted line extension of the lines A and B during low or high blower operation. Thus there is provided novel means for effecting an increased pressure setting during operation of the supplemental fluid injection system including novel means for automatically resetting the manifold pressure to a safe dry operating pressure in the event of water pressure or supply failure.

The relation of the several pressure setting programs may be, of course, varied within limits by adjustment of the screws 95 and 96, while the maximum pressure limit effective during non-operation of the supplemental fluid injection system, may be varied by appropriate adjustment of the screws 111 and 112.

What is claimed is:

1. For use with an aircraft engine having a pilot's main control element; a regulator comprising, in combination, condition responsive means for automatically adjusting a control device for said engine, a first control member for adjusting the datum of said automatic means in accordance with a first predetermined program and governed by the position of said main control element, a second control member for alternately adjusting the datum of said automatic means in accordance with a different second predetermined program and governed by the position of said main control element, means for limiting the adjustment of both of said members, and an

other condition responsive means for selectively placing said limiting means in and out of operative relation with said members.

2. For use with an aircraft engine having a pilot's main control element; a regulator comprising, in combination, condition responsive means for automatically adjusting a control device for said engine, a first control member for adjusting the datum of said automatic means in accordance with a first predetermined program, a second control member for adjusting the datum of said automatic means in accordance with a different second predetermined program, another condition responsive means for selectively placing said first and second control members in and out of operative relation with said automatic means, control lever means governed by the position of said main control element for adjusting said first and second control members, a member for limiting the adjustment of both of said first and second control members, and means for placing said limiting member in and out of operative relation with said control members.

3. For use with an aircraft engine having a pilot's main control element; a regulator comprising, in combination, condition responsive means for automatically adjusting a control device for said engine, a first control member for adjusting the datum of said automatic means in accordance with a first predetermined program, a second control member for adjusting the datum of said automatic means in accordance with a different second predetermined program, atmospheric pressure responsive means for selectively placing said first and second control members in and out of operative relation with said automatic means, and an operator-operative member limiting the adjustment of both of said control members under predetermined operating conditions.

4. For use with an aircraft engine having a pilot's main control element; a regulator comprising, in combination, a first condition responsive means for automatically adjusting a control device for said engine, first and second control members for adjusting the datum of said automatic means in accordance with different predetermined programs, second condition responsive means for placing said second control member in and out of operative relation, a member for limiting the adjustment of both of said control members, third condition responsive means for placing said limiting member in and out of operative relation, and said second control member so arranged as to control the datum of said automatic means over said first control member when in operative relation.

5. For use with an aircraft engine having a pilot's main control element; a regulator comprising, in combination, first condition responsive means for automatically adjusting a control device, for said engine, first and second control members for adjusting the datum of said automatic means in accordance with different predetermined programs, second condition responsive means for placing said second control member in and out of operative relation, a member for limiting the adjustment of both of said control members, third condition responsive means for placing said limiting member in and out of operative relation, said second control member when in operative relation arranged so as to control the datum of said automatic means over said first control member, and means governed by the position of said main control element for adjusting said first and second control members.

6. For use with an aircraft engine having a pilot's main control element; a regulator comprising, in combination, condition responsive means for automatically adjusting a control device for said engine, a control member for adjusting the datum of said automatic means, a plurality of cam members, means governed by the positions of said main control element for adjusting said cam members, followers for said cams, first spring means for biasing said cam followers into contacting relation with said cam members, second spring means for biasing said control member into contacting relation with one of said cam followers, actuating means for biasing said one cam follower out of contacting relation with one of said cams so that another of said cam followers may control the position of said control member, stop means for limiting the adjustment of both of said cam followers, and means for actuating said stop means in and out of operation.

7. For use with an aircraft engine having a pilot's main control element; a regulator comprising, in combination, condition responsive means for automatically adjusting a control device for said engine, a control member for adjusting the datum of said automatic means, a plurality of cam members, means governed by the position of said main control element for adjusting said cam members, followers for said cams, first spring means for biasing said cam followers into contacting relation with said cam members, second spring means for biasing said control member into contacting relation with one of said cam followers, actuating means for biasing said one cam follower out of contacting relation with one of said cams so that another of said cam followers may control the position of said control member, and operator-operative stop means for limiting the adjustment of both of said cam followers.

8. A regulator for the induction system of a supercharged aircraft engine, comprising, in combination, a boost control for regulating said induction system so as to maintain the pressure thereof at a predetermined value, first means for changing the datum of said boost control in accordance with a first predetermined program, second means for changing the datum of said boost control in accordance with a second predetermined program, and first condition responsive means for placing said first and second datum changing means in and out of operative relation, and second condition responsive means for changing the limits of said programs.

9. In a regulator, means for changing the datum of said regulator, comprising a plurality of cams, follower elements for said cams, a pivotally mounted control member for said regulator, first spring means biasing said cam follower elements into contacting relation with said cams, second spring means biasing said control member in an opposite direction into contacting relation with one of said cam follower elements, means for actuating said one element out of contacting relation with said control member so as to permit another of said elements to control the position of said control member, and thereby the datum of said regulator and means for actuating both of said elements out of contacting relation with said cams.

10. In a regulator, means for changing the datum of said regulator, comprising a pair of rotatably mounted cams, follower elements for each of said cams, a pivotally mounted control member adjustably positioned for changing the datum of said regulator, first spring means biasing said cam

follower elements into contacting relation with said cams, second spring means biasing said control member in an opposite direction, one of said cam follower elements limiting the movement of said control member in said opposite direction, motor means for releasably actuating the other follower element out of contacting relation with one of said cams, another motor means for releasably actuating both of said follower elements out of contacting relation with said cams.

11. A throttle control for supercharged aircraft engines, comprising a pilot's control lever, an induction throttle valve, means connecting said lever to said throttle valve, a boost control connected to said connecting means and arranged to vary the position of said throttle valve relatively to that of said control lever according to the intake manifold pressure of said engine, first means for changing the datum of said boost control in accordance with a first predetermined program, second means for changing the datum of said boost control in accordance with a second predetermined program, means for operating said first and second datum changing means simultaneously by said pilot's control lever, means for selectively placing said first and second datum changing means in and out of operative relation with said boost control in accordance with altitude, and means for independently placing both of said datum changing means out of operative relation with said boost control.

12. A throttle control for supercharged aircraft engines, comprising a pilot's control lever, an induction throttle valve, means connecting said lever to said throttle valve, a boost control connected to said connecting means and arranged to vary the position of said throttle valve relatively to that of said control lever according to the intake manifold pressure of said engine, first means for changing the datum of said boost control in accordance with a first predetermined program, second means for changing the datum of said boost control in accordance with a second predetermined program, means for operating said first and second datum changing means simultaneously by said pilot's control lever, means for selectively placing said first and second datum changing means in and out of operative relation with said boost control in accordance with an operating condition of said engine, and other means for placing both of said datum changing means out of operative relation with said boost control.

13. In an aircraft internal combustion engine of the type including a carburetor for supplying a combustible mixture to said engine, a supercharger for supplying air to the induction system of said engine, operable means for injecting a supplemental fluid for suppressing predetonation of said engine, and means for regulating the pressure in the induction system of said engine; the improvement comprising first means for changing the datum of said regulating means, second means for changing the datum of said regulating means, a pilot's control lever operably connected to said first and second datum changing means, means for limiting the control of said regulating means by said first and second means, and fluid pressure responsive means for releasing said limiting means during the operation of said supplemental fluid injection means, and said fluid pressure responsive means arranged so as to return said limiting means to operative relation upon cessation of operation of said supplemental fluid injection means.

14. In an aircraft internal combustion engine

of the type including a carburetor for supplying a combustible mixture to said engine, a supercharger for supplying air to the induction system of said engine, means for changing the driven speed of said supercharger, operable means for injecting a supplemental fluid for suppressing predetonation of said engine, and means for regulating the pressure in the induction system of said engine; the improvement comprising first means for changing the datum of said regulating means, second means for changing the datum of said regulating means, a pilot's control lever operably connected to said first and second datum changing means, atmospheric pressure responsive means operatively connected to said speed changing means so as to change the driven speed of said supercharger from a first to a second driven speed at a predetermined atmospheric pressure, and said atmospheric pressure responsive means arranged so as to place the first of said datum changing means in control of said regulating means at the first driven speed and the second of said datum changing means in control of said regulating means at the second driven speed, 25 means for limiting the control of said regulating means by said first and second means, and supplemental fluid pressure responsive means for releasing said limiting means during operation of said supplemental fluid injection means.

15. In an aircraft internal combustion engine of the type including a carburetor for supplying a combustible mixture to said engine, a supercharger for supplying air to the induction system of said engine, means for changing the driven speed of said supercharger, operable means for injecting a supplemental fluid for suppressing predetonation of said engine, and means for regulating the pressure in the induction system of said engine; the improvement comprising first 30 means for changing the datum of said regulating means, second means for changing the datum of said regulating means, a pilot's control lever operably connected to said first and second datum changing means, manually operable means for changing the speed of said supercharger from a first to a second driven speed and said manually operable means so arranged as to place the first of said datum changing means in control of said regulating means at the first driven speed and the second of said datum changing means in control of said regulating means at the second driven speed, means for limiting the control of said regulating means by said first and second means, and supplemental fluid pressure responsive means for releasing said limiting means during operation of said supplemental fluid injection means.

16. In an aircraft internal combustion engine of the type including a carburetor for supplying a combustible mixture to said engine, a supercharger for supplying air to the induction system of said engine, means for changing the driven speed of said supercharger, operable means for injecting a supplemental fluid for suppressing predetonation of said engine, and means for regulating the pressure in the induction system of said engine; the improvement comprising first means for changing the datum of said regulating means, second means for changing the datum of said regulating means, a pilot's control lever operably connected to said first and second datum changing means, control means for changing the speed of said supercharger from a first to a second driven speed, and said control means so arranged as to place the first of said datum changing means in control of said regulating

means at the first driven speed and the second of said datum changing means in control of said regulating means at the second driven speed, means for limiting the control of said regulating means by said first and second means, and supplemental fluid pressure responsive means for releasing said limiting means during operation of said supplemental fluid injection means.

17. In an aircraft internal combustion engine of the type including a supercharger for supplying air to the induction system of said engine, means for changing the driven speed of said supercharger, and means for regulating the pressure in the induction system of said engine; the improvement comprising first means for changing the datum of said regulating means, second means for changing the datum of said regulating means, a pilot's control lever operably connected to said first and second datum changing means, operable means controlled to said speed changing means and arranged to change the driven speed of said supercharger from a first to a second speed, and said operable means arranged so as to place the first of said datum changing means in control of said regulating means at the first driven speed of said supercharger and the second of said datum changing means in control of said regulating means at the second driven speed of said supercharger, and releasable means for preventing the maximum pressure setting of said first and second datum changing means from exceeding predetermined values.

18. In an aircraft internal combustion engine of the type including a supercharger for supplying air to the induction system of said engine, means for changing the driven speed of said supercharger, and means for regulating the pressure in the induction system of said engine; the improvement comprising first means for changing the datum of said regulating means, second means for changing the datum of said regulating means, a pilot's control lever operably connected to said first and second datum changing means, atmospheric pressure responsive means connected to said speed changing means and arranged to change the driven speed of said supercharger from a first to a second speed, and said atmospheric pressure responsive means arranged so as to place the first of said datum changing means in control of said regulating means at the first driven speed of said supercharger and the second of said datum changing means in control of said regulating means at the second driven speed of said supercharger, and releasable means for limiting the maximum pressure setting of said datum changing means.

19. In an aircraft internal combustion engine of the type including a carburetor for supplying a combustible mixture to said engine, a supercharger for supplying air to the induction system of said engine, means for changing the driven speed of said supercharger, operable means for injecting a supplemental fluid for suppressing predetonation of said engine, and means for regulating the pressure in the induction system of said engine; the improvement comprising a shaft, a pair of cams mounted on said shaft, a pilot's control lever operably connected to said shaft, follower elements for each of said cams, a pivotally mounted frame for controlling the datum of said regulator, first spring means for biasing said cam follower elements into contacting relation with said cams, second spring means for biasing said control frame in an opposite direction, one of said cam follower elements limiting the movement of said control frame in said opposite direction, a first motor means for actuating one of the cam follower elements into an inoperative relation during operation of the supercharger at a first driven speed and into a position controlling the position of said control frame at a second driven speed, operable means for controlling the first motor means, a pivotally mounted second frame so arranged as to limit the extent of movement of said follower elements under the biasing force of said first spring means, third spring means for biasing said second frame into an inoperative position, a second motor means for effecting movement of said second frame into an operative and inoperative relation, supplemental fluid pressure responsive means for controlling the operation of said second motor means and so arranged as to cause said second motor means to effect movement of said second frame into an operative position for limiting the position of said cam follower elements during the inoperation of the supplemental fluid injection means and into a non-limiting position during the operation of the supplemental fluid injection means.

Certificate of Correction

Patent No. 2,453,654.

November 9, 1948.

HAROLD ARTHUR WHEELER

It is hereby certified that errors appear in the printed specification of the above numbered patent requiring correction as follows:

Column 17, line 42, claim 4, strike out "a" before the word "first"; line 61, claim 5, strike out the comma after the syllable "vice"; column 18, line 7, claim 6, for "positions" read *position*; line 46, claim 8, for "sec-" read *second*; line 49, strike out "program," second occurrence;

and that the said Letters Patent should be read with these corrections therein that the same may conform to the record of the case in the Patent Office.

Signed and sealed this 22nd day of March, A. D. 1949.

[SEAL]

THOMAS F. MURPHY,
Assistant Commissioner of Patents.

Certificate of Correction

Patent No. 2,453,654

November 9, 1948

HAROLD ARTHUR WHEELER

It is hereby certified that error appears in the printed specification of the above numbered patent requiring correction as follows:

Column 21, line 20, for the word "controlled" read *connected*;
and that the said Letters Patent should be read with this correction therein that the same may conform to the record of the case in the Patent Office.

Signed and sealed this 14th day of February, A. D. 1950.

[SEAL]

THOMAS F. MURPHY,
Assistant Commissioner of Patents.
